FOREIGN PATENT DOCUMENTS

DE 3139463 A1 * 4/1983

* cited by examiner

Primary Examiner — Rashida Johnson*(74) Attorney, Agent, or Firm* — QuickPatents, Inc.; Kevin Prince(57) **CLAIM**

We claim the ornamental design for an exercise garment, as shown and described.

DESCRIPTION

FIG. 1 is a perspective view of an exercise garment, showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines showing a person in FIG. 1 and design elements in FIGS. 1, 2 and 4 depict environmental matter and form no part of the claimed design.
